UNITED STATES PATENT OFFICE.

HARRY L. ALLEN, OF ALLIANCE, OHIO, ASSIGNOR TO AMERICAN STEEL FOUNDRIES,
OF NEW YORK, N. Y., A CORPORATION OF NEW JERSEY.

CAR-TRUCK.

1,173,402.

Specification of Letters Patent. Patented Feb. 29, 1916.

Application filed December 13, 1915. Serial No. 66,564.

To all whom it may concern:

Be it known that I, HARRY L. ALLEN, a citizen of the United States, and resident of Alliance, in the county of Stark and State 5 of Ohio, have invented certain new and useful Improvements in Car-Trucks, of which the following is a specification.

My invention relates to car trucks, and has particular reference to a novel bolster 10 and sideframe construction.

It is common practice to cast the sideframes used in car trucks and to mount the bolsters in such manner that their ends are fitted in and guided by the frames in their 15 vertical reciprocation. It has been found, likewise, that considerable wear takes place, which finally results in the loss of the sideframes of bolsters.

An object in the present construction is 20 to provide hardened steel wearing surfaces in both the bolster and sideframe, such hardened portions being cast as a part of the structures. The wearing surfaces may in this manner be formed of a metal which is 25 extremely hard and resistent to wear, while the remaining portions of the sideframe and bolster may be of the usual mild steel especially adapted for the strains to which such members are subjected.

30 The invention will be more readily understood by reference to the accompanying drawings, wherein—

Figure 1 is a side elevation of a sideframe and bolster, the bolster being shown in section; Fig. 2 is a fragmentary plan view of the sideframe and bolster, the sideframe being broken away at a point above the bolster; Fig. 3 is a perspective view of the 35 insert for the bolster, and Fig. 4 is a perspective view of the insert for the columns 40 of the sideframe.

In the drawings, a conventional form of cast sideframe is shown having a compression member 10, tension member 11 and 45 struts 12. The struts 12 form column guides between which the bolster 13 is mounted for vertical reciprocation. The bolster is provided on its side with lugs or lips 14, which bear against the sides of the columns, the 50 bolster being inserted by passing the end thereof through the enlarged portion 15 of the sideframe. The upper inner portions of the columns or struts are bounded by the hard steel U-shaped plates 16, having coun-

tersunk openings 17, 18, in the front and 55 sides thereof. These plates are located in the proper position in the mold and the molten steel allowed to flow therearound, the metal entering the countersunk openings and occupying the countersunk portions 60 thereof. This in effect rivets the plate to the sideframe in a secure manner.

Likewise, the wearing faces of the bolster are reinforced between the lugs 14 by locating a plate 19 therein, this plate being 65 provided with countersunk openings 20. This plate, which is formed of a hard and wear-resisting steel, is likewise located in the mold in proper position and the metal allowed to flow therearound, thereby securely 70 riveting the plate to the bolster. When the castings are finished, the parts which are subject to wear will be found to be suitably reinforced by a hard steel, which is in effect 75 an integral part of the casting.

It will be apparent that the means of securing the wear plate in position may be varied, and such modifications as are within the scope of my claims I consider within 80 the spirit of my invention.

I claim:

1. In a car truck, the combination of a cast bolster and sideframe adapted for relative vertical reciprocation, the engaging portions of said bolster and sideframe being 85 reinforced, the reinforcing means including hardened steel plates cast in the desired location, substantially as described.

2. In a car truck, the combination of a cast metal side frame and bolster, said bolster engaging the sideframe and being adapted for vertical reciprocation therein, and hardened steel wear plates cast in place in the guiding columns of the sideframe at the point of engagement with said bolster, substantially as 95 described.

3. In a sideframe, the combination of compression member, tension member and strut, all formed in a single casting, and a hard metal wearing plate bounding the edges 100 of the struts at their upper portions and rigidly held in place by being cast in position, substantially as described.

4. In a sideframe, the combination of compression member, tension member and struts 105 forming columns, and a hard metal wear plate of channel shape in cross section applied to the upper portions of said columns,

said wear plates being provided with countersunk apertures and being adapted to be located in the mold, and the metal of the sideframe allowed to flow into said countersunk opening, thereby, in effect, riveting said wear plate to said columns, substantially as described.

Signed at Alliance, Ohio, this 6th day of December, 1915.

HARRY L. ALLEN.
